UNITED STATES PATENT OFFICE.

WILLIAM B. RUSSELL, OF PHILADELPHIA, PENNSYLVANIA.

HEDDLE.

No. 825,244.

Specification of Letters Patent.

Patented July 3, 1906.

Application filed June 22, 1905. Serial No. 266,435.

To all whom it may concern:

Be it known that I, WILLIAM B. RUSSELL, a citizen of the United States, residing at Philadelphia, in the county of Philadelphia and State of Pennsylvania, have invented 5 certain new and useful Improvements in Heddles; and I do declare the following to be a full, clear, and exact description of the invention, such as will enable others skilled in the art to which it appertains to make and use the same.

My invention relates to improvements in heddles, and more particularly to those for use in tapestry and velvet-carpet looms.

15 The object of the invention is to provide a heddle of this character which when worn out at one end may be reversed, so that its life will be doubled.

With the above and other objects in view 20 the invention consists of certain novel features of construction, combination, and arrangement of parts, as will be hereinafter described and claimed.

In the accompanying drawings, Figure 1 is 25 a side view of my improved heddle. Fig. 2 is an edge view of the same, and Fig. 3 is a transverse sectional view taken on the line 3 3 in Fig. 1.

Referring to the drawings by numeral, 1 30 denotes my improved heddle, which is preferably constructed from a flat piece of steel and has adjacent to each of its ends elongated openings or slots 2 to receive the rods which retain it in the heddle-frame. The central portion of the heddle is twisted slightly, 35 as clearly shown in Figs. 2 and 3 of the drawings, to allow the warps to work free and yet at the same time very close together. In this twisted central or intermediate portion 3 of the heddle is formed a long longitudinally-extending slot 4 to receive the stuffer-warp, and adjacent to each end of said slot 4 is formed 40 an opening 5 to receive the print-warp. It will be understood that only one of the openings 5 is used at a time, that one 45 being the uppermost; but I provide two of said openings, so that when the upper end of the slot 4 and its adjacent opening 5 are worn out the heddles may be reversed by in-

verting the heddle-frame and employing the 50 opposite end of the slot 4 and its adjacent opening 5. Since the wear of the warps of the heddles is only at the upper portion, the provision of the opening or eye 5 at each end of the slot 4 will permit the double use of the 55 heddles. This heddle is free from any notches or indentations that will break the warp-threads, and it will not stretch or break from the strain of the warps.

From the foregoing description, taken in 60 connection with the accompanying drawings, the construction and operation of the invention will be readily understood without requiring a more extended explanation.

While this heddle is particularly adapted 65 for use on tapestry and carpet looms, it will be understood that it may be employed upon looms of other kinds. It will also be understood that various changes in the form, proportion, and the minor details of construction 70 may be resorted to without departing from the principle or sacrificing any of the advantages of this invention.

Having thus described my invention, what I claim as new, and desire to secure by Letters Patent, is—

1. A heddle having intermediate its ends a slot for the stuffer-warp and adjacent to each end of said slot an opening for the print-warp, whereby when said heddle is worn out 80 at one end it may be reversed.

2. A heddle consisting of a flat metal strip having a slightly-twisted central portion and openings adjacent to its ends to permit it to be attached to a heddle-frame, said twisted 85 central portion being formed with a longitudinally-extending slot for the stuffer-warp and adjacent to each end of said slot with an opening for the print-warp, whereby when said heddle is worn out at one end it may be reversed. 90

In testimony whereof I have hereunto set my hand in presence of two subscribing witnesses.

WILLIAM B. RUSSELL.
